(57) **CLAIM**

The ornamental designs for an absorbent pants having a boy-short design, as shown and described.

DESCRIPTION

FIG. 1 is a front elevational view of an embodiment of an absorbent pants embodying my new boy-short design;

FIG. 2 is a front perspective view of the absorbent pants in FIG. 1;

FIG. 3 is a rear perspective view of the absorbent pants in FIG. 1; and,

FIG. 4 is a rear elevational view of the absorbent pants in FIG. 1.

The broken line showing of an absorbent pants having a boy-short design is included for the purpose of illustrating environmental structure and forms no part of the claimed design.
